Elevin J. Ney, of Lowell, Mass.

Ass'tant to

The Lowell Manufacturing Company,

Letters Patent No 16571 dated, Aug 19, 1862.

The schedule referred to in these Letters Patent and making part of the same.

To all whom it may concern:

Be it known that of Elevin J. Ney, of Lowell, in the County of Middlesex and State of Massachusetts, have originated and designed a new pattern for carpets or other fabrics, of which the following is a full, clear and exact description, reference being had to the accompanying drawings, making part of this specification.

1. and 2, in the corners are groups of flowers and leaves resting on the veined leaves A. A. Surrounding these veined leaves, are broad belts B and C, formed of small dots diminishing in size from the inside to the outside edges.

D, in the centre is a group of fruit and leaves.

In the corners 3 and 4, are fourths of rosettes resting on the blocks E and F. Block E, is surrounded by the wreath 5. Block F, is surrounded by the wreath 6, which slightly overlaps the belt C, and underlies the belt B.

The difference existing between this design and that designated as "application D" issued Dec. 18th, 1860, is as follows: The sprigs which extend inwardly from the wreath 6, occupy the space which is designated in application D as "the ground C", and further, in this design, the wreath 6, underlies a part of the belt B, whereas in application D, the corresponding wreath F, slightly overlaps the belt B.

The colors employed for the different portions of the design, may be varied to suit the taste and wish of the manufacturer.

Claim.

What I claim as my invention and desire to secure by Letters Patent, is the design or pattern for carpets or other fabrics, herein set forth.
